HEAT EXCHANGER

Trifon Vassiliou, East Orange, N. J.

Application November 27, 1941, Serial No. 420,711

5 Claims. (Cl. 183—32)

This invention relates to air heaters.

An object of this invention is to provide a heater embodying a plurality of air ducts which are adapted to be immersed in a heating medium, such as hot water or steam, and a blower for forcing the air through the ducts.

Another object of this invention is to provide a heater of this type which has the air ducts thereof secured to a head so that the ducts may be removed as a unit for replacement or repair of the ducts.

A further object of this invention is to provide a device of this kind which can be used either as a heater or a cooler to thereby provide either heated or cooled air.

A further object of this invention is to provide in a device of this kind improved intake and outlet manifolds which are connected to and support the air ducts within the boiler.

A further object of this invention is to provide in a device of this kind an improved protecting means about the air ducts, so that when the device is used as a cooler ice may be placed in the boiler and the ice held from direct contact with the air ducts, the latter being immersed in either cold water or a cooling brine.

A further object of this invention is to provide a heating unit of simple construction, so that if desired, it may be placed directly within the room to be heated.

To the foregoing objects and others which may hereinafter appear, the invention consists of the novel construction, combination and arrangement of parts as will be more specifically referred to and illustrated in the accompanying drawings, but it is to be understood that changes, variations and modifications may be resorted to which fall within the scope of the invention as claimed.

In the drawings:

Figure 1 is a plan view partly broken away of the heater with certain parts thereof removed,

Figure 2 is a sectional view taken on the line 2—2 of Figure 1, and

Figure 3 is a sectional view taken on the line 3—3 of Figure 2.

Referring to the drawings the numeral 10 designates generally a boiler structure or water heater comprising an inner shell 11, an outer shell or jacket 12 and an insulating wall 13 disposed between the inner and outer shells or jackets 11 and 12. The boiler 10 is provided with a bottom wall 14, and the bottom wall 14 has secured thereto a flared annular base member 15 formed with an outer annular flange 16 encompassing the outer

jacket 12. A burner or heating means 17 in the form of a gas burner is disposed in the chamber 18, formed below the bottom wall 14 and the burner 17, and is adapted to be connected by means of a pipe 19 to a suitable source of fuel supply.

10 A head or top wall 20 is disposed on the upper end of the boiler 10, the head 20 being formed as a flat disk, and the outer portions of the head 20 are adapted to be secured by fastening devices 21 to an outwardly extending annular flange 22 which is formed integral with the inner boiler or container 11. A water gauge 23 is secured to the boiler 10 below the head 20 and is provided with upper and lower fittings 24 and 25 which extend through the jacket 12 and the inner container 11. A safety valve 26 is connected to the boiler 10 adjacent the upper portion thereof, so as to relieve any pressure formed by steam or the like in the upper portion of the boiler. Preferably the safety valve 26 is of such a construction as to relieve the boiler 10 from a very low steam or other fluid pressure which may accumulate above the water line 27.

15 20 25 In order to provide a means whereby the water in the boiler 10 may heat air, I have provided an air heating unit which is fixed relative to the head 20 and forms a part of the head 20, so that the air heating unit to be hereinafter 30 described may be furnished as a new article of manufacture for a water heater or cooler, and inserted within the heater or cooler for providing the proper heat exchange to either heat or cool the air passing through the unit. The heating 35 unit as shown in Figure 1 comprises a plurality of depending funnel-shaped air intake members 28 which are provided with cylindrical upper end portions 29 positioned in annularly arranged openings 30 formed in the head 20 at one side of 40 the axial center of the head.

The intake members 28 are adapted to be welded as at 31 to the head 20, and each intake member 28 is provided at its lower end with a flared nipple 32. The nipple 32 has its larger 45 end lowermost, and one end of an air duct or pipe 33 is adapted to be tightly engaged within the nipple 32. Preferably the air duct 33 is split as at 34, so that the end of the duct 33 may be pushed into the nipple 32 and frictionally held 50 therein. This construction permits the ready insertion and removal of the air duct relative to the intake member 28, so that if it is necessary to replace one or more of the air ducts, the air duct may be pulled out from the nipple 32, 55 and a new duct quickly inserted therein. The

air ducts 32 are of like construction and are U-shaped as shown in Figure 1, the intake leg 35 of each air duct being disposed in a vertical position, and the bight 36 of each air duct being of longitudinally arcuate configuration and terminating in a vertical outlet duct 37.

The outlet duct 37 is connected at its upper end to an outlet funnel-shaped member 38 which is similar to the intake member 28, and is secured in any suitable manner within an opening 39 formed in the head 20 diametrically opposite from the series of intake members 28. The construction of the outlet members 38 is similar in every detail to the construction of the intake members 28 shown more specifically in Figure 3, the upper outlet end of each air duct 33 being frictionally held within the lower oppositely flared end 40 of each outlet member 38.

An upstanding intake nipple 41 is secured to the upper side of the head 20 and encompasses the upper open ends of the intake members 28. A pipe 42 is adapted to telescope over the nipple 41, and a fan 43 is mounted within the pipe 42 being operated by a fan motor 44 supported by brackets 45 within the interior of the pipe 42. The fan 43 is adapted to force air downwardly through the intake nipple 41, and by reason of the funnel-shaped intake members 28, the air in the nipple 41 will be compressed, and will be forced downwardly through the air ducts 33. The air ducts 33, being substantially entirely immersed in the hot water within the boiler 10, will become heated thereby, so that the air passing through the air ducts 33 will be heated and will be discharged from the outlet members 38 into an outlet nipple 46.

An outlet air conducting pipe 47 has one end thereof telescoping over the outlet nipple 46, and the pipe 47 may be continued to any desired point where the heat is desired. The outlet nipple 46 is adapted to be secured as by welding or other suitable fastening means to the upper side of the head 20, and the nipple 46 encloses or encompasses the open upper ends of the outlet members 38.

In order to provide a means whereby the air ducts 33 may be suitably protected against damage during the shipment of the heating unit, comprised of ducts 33 and the head 20 when this unit is disconnected from the boiler 10, I have provided a perforate protecting shield 48 which encloses the group of air ducts 33, and extends downwardly into the interior of the boiler 10. The shield 48 is provided with an outwardly extending annular flange 49 at its upper end, which is secured to an annular ring 50 interposed between the head 20 and the flange 22.

The shield 48 provides a means whereby in the event ice or other cooling medium is inserted within the boiler 10, the ice will be out of direct contact with the air ducts 33, so that the ice cannot injure the air ducts, whereas the cold water derived from the ice may freely pass through the shield 48 for contact with the outer surface of the ducts 33.

The head 20 is provided in the axial center thereof with an annular opening 51 which is normally closed by a closure plate 52 having a rabbet 53 engaging within the opening 50. The interior of the boiler 10 may be cooled, so that the air passing through the ducts 33 may also be cooled by suspending a cooling unit 54 from the closure plate 52. The cooling unit 54 may be connected to a suitable refrigerator mechanism, and preferably the cooling unit 54 is sus-

pended from the plate 52 by pipes 55 and 56 which are adapted to be connected to the cooling system of the refrigerator unit.

In the use and operation of this device the water in the boiler 10 is preferably disposed at the water level designated by the numeral 27. The water is heated by the burner 17 and as soon as the water becomes heated to the desired degree, the fan motor 44 may be operated so as to force cool air through the air ducts 33. This cool air will be heated in the passing through the air ducts 33, and will be discharged into the outlet nipple 46 from which point the heated air may be conducted by means of the pipe 47 to the desired point.

With a construction of this kind the water in the boiler 10 may be heated to a predetermined degree by means of the burner 17, and when this predetermined temperature of the water has been attained, the burner 17 may be cut off. In view of the fact that the hot water will dissipate its heat for a considerable period after the burner 17 has been cut off, the fan motor 44 may be continued in operation until the water drops to a predetermined low temperature whereupon the burner 17 may be again operated.

Where the construction hereinbefore described is used as a cooler with ice disposed within the boiler 10 and about the shield 48, the water in the boiler 10 may be maintained at a predetermined level by means of an overflow outlet pipe 57 which is disposed in a vertical position within the inner boiler member 11, and which is secured within the bottom 14 by fastening members 58. A discharge valve 59 is connected to an extension pipe 60 which is connected to the lower end of the overflow pipe 57.

The heating unit comprising the head 20, the air ducts 33 and the shield 48 may be constructed as a separable unit, so that this heating unit may be placed in any desired container for either heating or cooling the air passing through the ducts 33. The provision of the protecting shield 48 about the air ducts 33 will provide a means whereby the air ducts will be properly protected during the shipment of the heating unit, and also the placement of the unit within the boiler 10. In addition, the shield 48 will also protect the air ducts 33 when ice or the like is placed within the container or boiler 10.

In order to provide a means whereby the flow of air through the outlet nipple 46 may be regulated, a perforated damper 61 is mounted on a manually operable shaft 62 positioned above the nipple 46. This perforated damper also provides a means for filtering the air discharging from the air ducts 33.

What I claim is:

1. An air conditioning unit comprising an open top water container, a covering for said container, means for securing said cover to said container, said cover having a pair of radially opposed series of openings therethrough, funnel-shaped members secured at their larger ends in said openings and depending therefrom, a series of parallel U-tubes in said container, each having its opposite ends split and frictionally engaging in the smaller ends of said funnel-shaped members, a pair of upstanding collar flanges on the upper side of said cover each surrounding one of said series of openings, an inlet pipe secured to one of said flanges, means in said inlet pipe for forcing air through said U-tubes, an outlet pipe secured to the other of said flanges, means in said outlet pipe for filtering air passing

therethrough, and heat exchange means for varying the temperature of the water in said container whereby the temperature of said air is varied.

2. An air conditioning unit comprising, an open top water container, a cover removably secured to said container, said cover having a pair of radially opposed series of openings therethrough, funnel-shaped members secured at their larger ends in said openings and depending therefrom, a series of parallel U-tubes in said container, each having its opposite ends split and frictionally engaging in the smaller ends of said funnel-shaped members, a pair of upstanding collar flanges on the upper side of said cover each surrounding one of said series of openings, an inlet pipe secured to one of said flanges, an outlet pipe secured to the other of said flanges, means for forcing air through said U-tubes, and heat exchange means for varying the temperature of the water in said container whereby the temperature of said air is varied.

3. An air conditioning unit comprising, an open top water container, a cover for said container, means for securing said cover to said container, said cover having a pair of radially opposed series of openings therethrough, funnel-shaped members secured at their larger ends in said openings and depending therefrom, a series of parallel U-tubes in said container each having its opposed ends split and frictionally engaging in the smaller ends of said funnel-shaped members, an inlet pipe connected to one of said series of openings in said cover, an outlet pipe se-

cured to the other of said series of openings in said cover, and heat exchange means for varying the temperature of water in said container whereby the temperature of said air is varied.

5. 4. An air conditioning unit comprising, an open top water container, a cover for said container, means for securing said cover to said container, said cover having a pair of radially opposed series of openings therethrough, funnel-shaped members secured at their larger ends in said openings and depending therefrom, a series of parallel U-tubes in said container each having its opposite ends split and frictionally engaging in the smaller ends of said funnel-shaped members, 10 means for forcing air through said U-tubes, and heat exchange means for varying the temperature of the water in said container whereby the temperature of said air is varied.

5. In an air conditioning unit of the type including an open top water container and heat exchange means for varying the temperature of the water in said container; an air conditioning unit comprising, a cover removably secured to the top of said container, a pair of radially opposed upstanding collar flanges secured to the upper side of said cover, a series of openings through said cover internally of each of said flanges, funnel-shaped members secured at their larger ends in said openings and depending therefrom, and a series of air conditioning U-tubes in said container, each having its opposite ends split and frictionally engaging in the smaller ends of said funnel-shaped members.

TRIFON VASSILIOU.
